United States Patent Office.

JOHN CLARKE, OF REDDITCH, ENGLAND.

Letters Patent No. 78,059, dated May 19, 1868.

IMPROVEMENT IN WRAPPERS FOR NEEDLES.

The Schedule referred to in these Letters Patent and making part of the same.

TO ALL WHOM IT MAY CONCERN:

Be it known that I, JOHN CLARKE, of Redditch, in the county of Worcester, and Kingdom of England, needle-manufacturer, a subject of her Britannic Majesty, have invented "Improvements in Wrappers or Envelopes for Needles;" and I do hereby declare that the following is a full and exact description of my said invention; that is to say—

This invention consists in making wrappers or envelopes for needles, in such manner that a sheath or needle-case is so connected at its one end to an envelope or outer wrapper or case as to form a sort of hinged part upon such envelope or outer wrapper, so that when the outer wrapper is opened, and the ends of the needles exposed, the opening outward, and consequent pressure of the bottom part of the outer wrapper, and lower end of the sheath or needle-case, will cause such sheath to spring forward into a vertical position, enabling the needles to be selected and extracted therefrom with great facility.

The object and nature of this invention will be better understood by reference to the drawings hereunto attached.

Figure 1 shows a wrapper or envelope for needles, formed as already specified, with the parts thrown open to show the outlines of the same.

a is the sheath or needle-case, connected at its one end, *a'*, to an envelope or outer wrapper, *b*, so as to form a sort of hinged part upon the envelope or outer wrapper *b*. The outer wrapper *b* consists of two closing or folding side-wings, 1 2, which fold one upon the other and the needle-sheath *a*, as seen at fig. 2. The outer wrapper *b* also consists of a bottom or tail-piece, 3, for folding up and upon the side-pieces 1 2, and the needle-sheath *a*, and a top flap-piece, 4, the end of which passes into the free end or bottom of the tail-piece 3 upon the closing of the wrapper, and secures it; fig. 3 showing the wrapper closed.

When the outer wrapper *b* is opened, and the ends of the needles exposed, the opening outward and consequent pressure of the bottom part 3, and the lower end of the sheath or needle-case *a*, will cause such sheath *a* to spring forward into a vertical position, as shown at fig. 4, enabling the needles to be selected therefrom with great facility.

Figure 5 shows the envelope or needle-case in perspective when opened and in position for use.

I claim the sheath *a*, applied to the wrapper *b*, to operate in the manner and for the purpose substantially as set forth.

The above specification of my invention signed by me, this tenth day of February, in the year of our Lord one thousand eight hundred and sixty-eight.

JOHN CLARKE.
